UNITED STATES PATENT OFFICE.

ALFRED C. REX, OF PHILADELPHIA, PENNSYLVANIA.

TOY SAFE.

SPECIFICATION forming part of Letters Patent No. 358,697, dated March 1, 1887.

Application filed June 5, 1886. Serial No. 204,241. (No model.)

To all whom it may concern:

Be it known that I, ALFRED C. REX, a citizen of the United States, residing in Philadelphia, Pennsylvania, have invented certain Improvements in the Construction of Toy Safes, of which the following is a specification.

My invention consists of certain improvements in the construction of toy safes, as fully described hereinafter.

- 10 In the accompanying drawings, Figure 1 is a vertical section of a toy safe embodying my improvement. Fig. 2 is a transverse section, at right angles to that shown in Fig. 1, of the upper part of the safe. Fig. 3 is a view of the working parts of the lock with the cover-plate removed. Fig. 4 is a perspective view of one of the notched wheels, its spindle, and operating-disk; and Fig. 5 is a sectional plan view of the same.
- 20 The four side walls, A, and the top A' and bottom A" of the safe are made of suitable castings, riveted or otherwise secured together in any convenient way.

In the top plate of the safe is formed the usual slit, a, for the introduction of the coins, and in order to prevent the abstraction of coins through this slit by the insertion of a knife-blade or otherwise, I provide, immediately below the slit and on each side of it in 25 the interior of the safe, a pendent hinged flap, b, free to swing in either direction, so that if the safe is turned upside down one or other of the flaps will close the slit, and if a knife-blade is introduced to assist in withdrawing a coin one or other of the flaps will push the coin off the blade as the latter is withdrawn. As a 30 convenient way of hinging these pendent flaps b to the under side of the top plate, I rivet to a suitable projection on the said top plate, as shown in Fig. 1, a frame, b', having notches for the reception of the pivot-pins cast on the flaps, Fig. 2. I have shown the projection to which this frame is riveted as being sufficiently close to one of the flaps to prevent the latter 35 from falling backward when the safe is turned over; but this is not essential.

The front plate of the safe is provided with the usual hinged door, D, having a sliding locking-bolt, d, controlled by a combination-lock, E. In the present case I have shown the lock as provided with three notched wheels, e, to act on the inner end of the bolt d, and

each having a large notch which, when brought into line with the others opposite the inner end of the bolt, will allow the latter, under 55 the action of its spring d', to slide inward and release the door, as will be readily understood on reference to Fig. 3.

The number of wheels may vary; but each is mounted on a separate stem, F, which passes 60 through the door, and is provided on the outside with an operating knob or disk, F'. The stems of the inner wheels are tubular, and fit over each other and the central stem of the outermost wheel, as illustrated in Fig. 1. The 65 portion of the stem on which each wheel is fitted is made many-sided, as shown in Figs. 3 and 4, and the central opening of the wheel is made to correspond, so that the combination once set can be readily changed at any time by 70 simply removing the inside cover-plate of the lock and taking the wheels off their stems and resetting them in other positions.

In order to insure the accurate fitting of these portions of the wheels and stems together, they are both cut out by punches and dies; and in order to permit of the cutting of the straight sides on the stems, a groove, f, is formed on the latter immediately behind the portion of the stem which is to be cut by the 75 die, to give the necessary clearance for the metal in cutting.

I prefer to construct the interior of the safe for the reception of drawers G G', as shown in Figs. 1 and 2. In the present case two drawers 85 are illustrated as being used, the upper one being supported upon an open frame-like plate, H, held at the corners in lugs h on the side plates and notches in the flanges i of the front plate, while the sides of the drawer G are guided 90 by horizontal ribs g, cast on the inside of the side plates. The bottom drawer, G', is guided by similar horizontal ribs, and is supported by vertical ribs g' on the bottom plate. The upper drawer may be used for the reception of 95 coins introduced through the top slit, a, while the lower drawer is used for bills or jewelry.

If preferred, in some cases the safe may be made without the top slit, and all the articles may be introduced into the drawers by opening the door of the safe.

I do not here claim the construction of the lock or any part thereof above described, as I have made that the subject of a separate ap-

lication for a patent filed by me October 15, 1886, Serial No. 216,822.

It has been proposed to provide within the top of a money-box, below the aperture for the insertion of the coins, curved springs intended by the narrowness of the space between the springs to prevent the withdrawal of the coins from the money-box. In my invention, however, it is not the narrowness of the space that prevents the extraction of the coin, but the falling of one or the other of the hinged flaps upon the knife-blade or other instrument inserted to withdraw the coin, and the consequent sweeping off of the coin as the instrument is withdrawn.

I claim as my invention—

1. A toy safe having a top slit and pendent flaps hinged on opposite sides of the slit on the inside, substantially as described.
2. The combination of the top plate of a toy safe having a slit with pendent flaps and

a supporting-frame for the flaps riveted to the under side of the top plate, substantially as described.

3. The combination of the sides of a toy safe having lugs *h* and a flanged front plate having notches with a plate, *H*, adapted to said lugs, and notches to form the shelf, substantially as described.

4. The combination of the side plates of a toy safe, having interior horizontal ribs *g*, and the bottom plate having vertical ribs *g'*, with drawers adapted to slide on the said ribs, substantially as described.

In testimony whereof I have signed my name to this specification in the presence of two subscribing witnesses.

ALFRED C. REX.
